UNITED STATES PATENT OFFICE.

JOSEPH ARMSTRONG, OF MALDEN, MASSACHUSETTS, ASSIGNOR TO AMERICAN MOISTENING COMPANY, OF BOSTON, MASSACHUSETTS, A CORPORATION OF MAINE.

HUMIDIFYING SYSTEM.

Application filed January 30, 1922. Serial No. 532,804.

To all whom it may concern:

Be it known that I, JOSEPH ARMSTRONG, a citizen of the United States, residing at Malden, in the county of Middlesex and 5 State of Massachusetts, have invented certain new and useful Improvements in Humidifying Systems, of which the following is a specification.

This invention relates to improvements in 10 humidifying systems. More especially it relates to an improved conditioning chamber of such a system. Where it is impracticable or less desirable to provide separate units for humidifying the atmosphere of a room, 15 it is customary to condition air in one or more large chambers usually located outside of the room, and to conduct it thence through main and branch pipes to the various portions of the room where it is discharged. 20 In such conditioning chambers various means have been provided for supplying the moisture, the most desirable of which, up to the present time, is a battery of jet-forming nozzles arranged to produce, by their 25 combined discharge, a curtain or screen of water vapor extending entirely across the chamber and through which the air may be forced under pressure, after having been previously passed over heating coils to make it more 30 susceptible to absorb more moisture in the chamber. After passing through this curtain, the air is, in a sense, super-saturated, for in addition to the moisture which it absorbs, and can carry, it has suspended in it 35 a great number of fine floating particles of water which later, unless means are provided to entrap them, either settle to the bottom of the ducts under the action of gravity, or are thrown against the walls of the ducts where 40 the direction of the latter turns sharply. The amount of these suspended or floating particles in the moistened air may be somewhat reduced by providing a series of eliminator plates across the discharge end of the 45 conditioning chamber. Although this is perhaps the most efficient method hitherto proposed, it is not entirely successful in removing the super-saturation, and does not wholly solve the problem of properly conditioning the air.

It is a fundamental feature of the present invention to provide means within the conditioning chamber whereby the dry air entering will be separated into two portions, one 50 of which will pass through the water jets

and emerge therefrom more or less super-saturated; and the other of which will pass by and continue beyond the jets, remaining as dry air until the two portions again commingle, whereupon the moisture-absorbing 60 capacity of the dry portion takes up the excess of moisture in the super-saturated portion, thereby producing a resultant mixture which may be of 100% relative humidity. This object is attained by arranging within 65 the conditioning chamber about the battery of nozzles, a plurality of hollow open-ended cylinders, one about each nozzle, with their axes parallel to the direction of flow of air. Each cylinder is of sufficient diameter to permit a suitable spread for the jet, but is long enough to extend beyond the region where the jet impinges upon its inner surface, thereby preventing each jet from contacting with its neighboring jets. The spaces between the cylinders constitute the passages 70 through which the dry air may flow past the jets without touching them to later mix with the wet air at the discharge end of the cylinders. The relative size of the cylinders 75 and the spaces between them can be predetermined to such a nicety for a given amount of water and air supply that the resultant mixture will have the most efficient degree of 80 humidity possible.

One form and arrangement of cylinders is shown in the drawings herewith, but these are to be considered as merely illustrative of but one embodiment of the invention. It is intended that the patent shall cover, by suitable expression in the appended claims, whatever features of patentable novelty exist 85 in the invention disclosed.

In the accompanying drawings:

Figure 1 is a side elevation of a conditioning chamber with a portion in section showing the arrangement of nozzles and cylinders within;

Figure 2 is a plan of Figure 1; and

Figure 3 is a view looking into the entrance end of the chamber.

Referring to the drawings, the chamber is shown as rectangular in cross section, having its top 10, bottom 12 and sides 14 made of sheet metal, and held together and reinforced by suitable angle-iron straps 16. Relatively dry air is introduced to this chamber from the left, as viewed in Figure 1, which after taking up moisture is discharged toward the right into suitable ducts 110

not shown. This air may be forced there-through either by pressure or by suction. Ordinarily, in a large chamber of the sort described, the moistening means comprise a 5 battery of nozzles 18 arranged close enough together for the jet from one nozzle to overlap the jets of adjacent ones, and for the jets of the peripheral nozzles to strike the walls of the chamber, thereby, in effect, forming 10 a continuous curtain or screen of water vapor over the entire cross section of the chamber through which the air must pass. This arrangement produces two undesirable results. It creates such a heavy, thick fog of moisture 15 particles, that an appreciable resistance to the flow of air is set up in the chamber making it necessary to increase the air-moving force and thus adding to the operating expense of the system. And the commingling 20 of the very fine particles forms a large number of relatively heavier particles, too large to be absorbed by the air, and yet sufficiently light to be carried along by it. Accordingly, the air passing through the vapor cur- 25 tain not only absorbs all the moisture it can, but in addition becomes burdened with a certain amount of these heavier suspended particles which later either settle to the bottom of the ducts or are thrown against the 30 side walls thereof at a turn. The collection of such particles eventually forms an appreciable quantity which flows along the duct, more or less of which ultimately drips therefrom to the possible damage of product 35 or fittings in the plant. Heretofore, it has been attempted to entrap these particles by arrangement of zig zag eliminator plates at the discharge end of the conditioning chamber. But these plates are also objectionable 40 in that they add still more resistance to the moving medium, and are unsuccessful in that they do not do the work thoroughly.

It has been demonstrated, as described in my pending application Serial No. 472,419, 45 that dry air can be introduced to a stream of saturated air to create a mixture having a higher moisture carrying capacity than that of the saturated air alone. If the stream of moistened air is in a state of over-satura- 50 tion, the injection of dry air thereinto can be of such quantity as to produce a mixture which will test to any desired degree of humidity. In the present invention a series 55 of cylindrical shells 21 are arranged in the conditioning chamber to provide separate sets of passages for the air that moves through the chamber, in one set of which the air passing through is super-saturated and in the other set of which it is maintained 60 dry until it is allowed to mix with the super-saturated air. As shown these hollow cylinders are disposed with uniformity about the chamber so that each is in contact with its neighbor, and those on the outer rows 65 rest against the walls of the chamber. All

may be pinned together and to the casings to hold them securely in place. Figure 3 shows clearly the preferred arrangement of the cylinders and nozzles in which each cylinder of an upper layer is vertically over 70 one in a layer below. The advantage of this, over a staggered or off-set arrangement, is that the discharge of excess water from the upper cylinder falls across the openings of the cylinders below, and not across the 75 discharge ends of the spaces between them, thus leaving these spaces free from moisture particles and permitting the dry air from the entrance end of the chamber to enter the major space beyond the cylinders in its 80 initial condition. Figure 3 also illustrates the relative proportion between the total part of the cross area circumscribed by the perimeters of the cylinders and the cross area of the spaces between them. 85

In operation, when the water is turned on in the header main 22, it flows through the feed pipes 24 to each nozzle and by it is jetted into the space confined by its cylinder in a conical spray against the cylinder walls. 90 The excess of water runs forward in the cylinder and falls to the bottom of the chamber which may be pitched downward and be provided with a hopper-like section 26 having a discharge pipe (not shown). The supply of dry air, with suitable velocity, enters the conditioning chamber behind the nozzles, and passes through both the cylinders and through the spaces between them. That flowing inside the cylinders is forced 100 through the conical jets of water and becomes highly saturated. In fact, as is usual with air passing through the fine spray of such a nozzle, the air is super-charged. The remainder of the air which passes through 105 the spaces between the cylinders reaches their discharge ends still dry, where it commingles with the super-charged air, immediately creating a mixture of greater moisture carrying capacity than that of the super-charged air alone. As a result the floating particles are absorbed by the new mixture and the whole moves on to the discharge end of the chamber. The state of 110 this air as regards saturation will depend on the relative size of the passages through and those between the cylinders, the dryness of the air that passes between, the fineness and quantity of the spray that is loaded upon the air in the cylinders, and the initial 115 dryness of the air entering the cylinders; but in general it is clear that the result will be a reduction of the super-saturation, and that the various elements can be adjusted so as to leave the air still saturated but better 120 able to carry the whole of its load of moisture without dropping it. Accordingly, the eliminator plates may be dispensed with, thus removing an element of resistance to 125 the draft through the system and making it 130

possible to reduce the power needed to move the air. The invention also provides for a further saving of power in that it not only does away with the continuous curtain of water across the chamber, thereby removing the resistance to air flow offered by such a water screen, but in that it also enables the discharge of the jet, circumscribed by the cylinder, to create a suction or draft therein, which acts both to draw air through it, and acts at the delivery end of the cylinder to help draw air through the spaces between cylinders, thus aiding in both ways the forced draft of the system.

15 This elimination of resistance and the addition of the jet-formed suction makes the use of a conditioning chamber, embodying the present invention, much less expensive than heretofore from the viewpoint of power consumption alone; and the absorption of the heavier moisture particles and the resulting formation of a properly humidified body of air, makes it highly economical in its use of water.

20 It is thus evident that with a given amount of water, a maximum amount of humidity can be imparted to a given quantity of air without having any unabsorbed particles of water suspended therein, and with a greatly reduced expenditure of power than heretofore required. The humidified air is of extremely even and uniform density due to the distribution of the cylinders and spaces throughout the cross section of the cylinders,

25 whereby there is a general distribution of dry air in the midst of the wet air emerging from the cylinders.

I claim as my invention:

1. A conditioning chamber of a humidifying system, comprising a casing for flow of air; straight dividing means therein, providing separate, straight parallel air passages; moistening means in one of said air passages whereby the air that is moving through it is super-saturated; there being another of said air passages which is free from moisture supply, whereby the air therein is conducted unchanged to the end of said dividing means; and there being, beyond said dividing means a discharge duct wherein there is freedom for the air from the said

separate passages to continue in the same direction for a distance in contiguity whereby the excess moisture is retained in the whole flowing body by absorption into the unmoistened air.

2. A conditioning chamber of a humidifying system having a battery of jet-forming nozzles for imparting moisture to a supply of moving air; an open ended passage for each of said nozzles, for directing a portion of said air through its jet; and other passages, among the first mentioned passages and delivering into the same major space, whereby a part of the air may flow past the jets unmoistened to commingle thereafter with the moistened air issuing from the first mentioned passages.

3. The combination, in a conditioning chamber of a humidifying system, with a battery of open ended cylinders distributed across the chamber with their axes in the direction of flow of air, of a battery of nozzles, one for the entrance end of each cylinder, adapted to form a conical jet therein spreading toward the discharge end of the cylinder; there being spaces between the cylinders whereby the air which does not enter the cylinders may continue past them in its initial condition to join the air passing through them after the latter has become thus moistened.

4. The combination, in a conditioning chamber of a humidifying system, with a battery of open ended cylinders distributed across the chamber with their axes in the direction of flow of air and with those above vertically over those below, of a battery of nozzles, one for the entrance end of each cylinder, adapted to form a jet therein spreading toward the discharge end of the cylinder, wherefrom the excess of water in that cylinder falls across the discharge end of a cylinder below; there being spaces between the cylinders whereby the air which does not enter the cylinders may continue past them in its initial condition to join the air passing through them after the latter has become thus moistened.

Signed at Boston, Massachusetts, this twenty-fourth day of January, 1922.

JOSEPH ARMSTRONG.
